UNITED STATES PATENT OFFICE

SAMUEL C. M. ANDERSON, OF DALLAS, TEXAS.

CHURN.

1,116,001.

Specification of Letters Patent.

Patented Nov. 3, 1914.

Application filed July 3, 1913. Serial No. 777,150.

To all whom it may concern:

Be it known that I, SAMUEL C. M. ANDERSON, a citizen of the United States, residing at Dallas, in the county of Dallas and State 5 of Texas, have invented certain new and useful Improvements in Churns, of which the following is a specification.

My invention relates to new and useful improvements in churns, and its object is to 10 provide a churn in which the milk will be thoroughly agitated through the opposite rotation of two dashers so constructed as to set the milk into a violent motion when rotated.

Another object is to provide a churn employing a glass containing vessel that will 15 permit the operator to observe readily the progress of the churning operation and which will adapt the churn to be readily 20 cleaned adding to its desirability from the viewpoint of sanitation.

A still further object of the invention is to provide a device of the character described that will be strong, durable, simple 25 and efficient and comparatively inexpensive to produce, also one in which the several parts will not be likely to get out of working order.

With the above and other objects in view, 30 the invention has relation to certain novel features of the construction and operation, an example of which is described in the following specification and illustrated in the accompanying drawing, wherein:

Figure 1 is a view showing my churn in 35 front elevation. Fig. 2 is a detail perspective view showing one of the dashers. Fig. 3 is a sectional end view of the other dasher taken upon the line X—X of Fig. 1. Fig. 4 is a detail sectional view taken upon the line 40 Y—Y of Fig. 1.

Referring now more particularly to the drawing, wherein like reference characters 45 designate similar parts in all the figures, the numeral 1 denotes a globular glass vessel formed with a large opening in its top encircled by a flange 1^a. Upon this flange is 50 fitted a cover 2 upon which is centrally surrounded a cast standard 4 rigidly secured to said cover by any suitable means. The upper extremity of the standard 4 is of semi-circular form as indicated at 4^a, a horizontal bar 4^b being mounted in a diametral

relation to said semi-circular portion, the parts 4^a and 4^b forming a handle. A horizontal sleeve 5 projecting integrally outward from the standard 4 is spaced some distance above the cover 2 of the vessel 1 and serves as a bearing for a shaft 6 adapted to be manually subjected to rotation by 55 a crank-arm 7, mounted upon the outer end of said shaft. Upon the other extremity of said shaft there is mounted fast a bevel gear 8. At its top and bottom, said gear respectively engages two bevel pinions 10 and 11, which are respectively fast and loose upon a vertical shaft 9 journaled at its upper end in the member 4^a and passing centrally through the base 9^a of the standard 4 and through the cover 2 into the vessel 1 extending to the bottom portion thereof. The pinion 11 is fast upon a sleeve 12 which sleeve projects slightly into the vessel 1 and projects a sufficient distance above the correlated pinion to serve as a truss 70 bearing for the pinion 10 preventing any downward displacement of the same and of the shaft 9 on which said pinion is fast. The pinion 11 is itself restricted from downward displacement due to the fact that 75 it rests rotatably upon the base 9^a.

Within the vessel 1, there is clamped to the lower end of the sleeve 12 a clamping bar 13 from the extremities of which a pair of vertical rods 14 extend rigidly downward 80 terminating substantially in the central portion of the vessel 1. The lower extremities of said rods carry a dasher member having an elongated central body 15 of square cross-section, said body being preferably disposed 85 with its diagonally opposite longitudinal edges respectively aligned horizontally and vertically. Upon each of the end faces of the body 15 a vertical paddle 16 is mounted fast, equidistant from the lateral edges of 90 the body. Upon the extremities of said body 15 a pair of inclined plates 17 are respectively secured, said plates being contiguous 95 respectively with the two under faces of said body and having their extremities projecting equidistantly beyond the body. Upon the lower extremity of the shaft 9 there is mounted a second dasher similar to that 100 comprised by the parts 15, 16 and 17 except for the fact that the plates 17 are in this 105 case secured to the two top surfaces of the

member 15 rather than to the under surfaces thereof.

The bottom of the vessel 1 is fitted with a drain valve 18 through which the liquid 5 contents of the vessel may be conveniently withdrawn.

When the crank 7 is turned, it is apparent from the above description that the shaft 9 and the sleeve 12 will be subjected to rotation in opposite directions so that the two dashers each comprising parts 15, 16 and 17 will also be oppositely rotated. The construction of the two dashers is such that their simultaneous rotation in opposite directions will produce a very violent agitation of the milk which is being churned, one portion thereof being whirled in one direction of rotation by the paddles 16 of the upper dasher and another portion being oppositely whirled by the paddles 16 of the lower dasher. That portion of the contents of the vessel lying between the two dashers will be very violently agitated due to a pressure acting downwardly from the upper 25 paddles 17 and a pressure acting upwardly from the lower paddles 17. The upper and lower faces of the body 15 will also force a portion of the milk upwardly and downwardly simultaneously whirling the same.

30 The use of the two separate dashers oppositely rotating as described gives to my churn an efficiency that makes it possible to

perform the operation of churning in a comparatively short time.

The exertion of very little manual effort 35 is required to maintain the above described churn in operation.

The invention is presented as including all such modifications and changes as properly come within the scope of the following 40 claims.

What I claim is:

1. In a churn dasher, an elongated horizontal member having a rectangular cross-section, vertical flat blades, one at each end of the member, and a pair of inclined plates secured to the ends of the member adjacent the blades. 45

2. In a churn dasher, an elongated horizontal member having a rectangular cross-section, vertical flat blades, one at each end of the member, and a pair of inclined plates secured to the ends of the member adjacent the blades, the plate at one end being inclined opposite to the plate at the other 50 end. 55

In testimony whereof I have signed my name to this specification in the presence of two subscribing witnesses.

SAMUEL C. M. ANDERSON.
